UNITED STATES PATENT OFFICE.

OLIN M. DANTZLER, OF GREENWOOD, SOUTH CAROLINA.

ENVELOPE SEALER.

Application filed April 19, 1927. Serial No. 184,917.

This invention relates to new and useful improvements in devices for use in the sealing of envelopes and aims to provide a highly novel, simple, and efficiently operating device in the form of a hand implement constructed for permitting of the rapid and proper moistening and sealing of an envelope.

An important object of this invention is to provide an implement of this character that is constructed for receiving the flap of an envelope and adapted to first moisten the gummy surface of the flap and then press the same tightly against the envelope body causing the same to positively adhere thereto.

A further and most important object is to provide an article of this character that is extremely simple in construction and therefore inexpensive of manufacture, the same embodying but relatively few parts and these so correlated as to reduce the possibility of disarrangement to a minimum.

With the foregoing and other objects in view as the nature of the invention will be better understood, the same comprises the novel form, combination and arrangement of parts hereinafter more fully described, shown in the accompanying drawing and claimed.

In the accompanying drawing wherein like numerals indicate corresponding parts:

Figure 1 is a view partially in front side elevation partially in longitudinal cross section of an envelope sealer constructed in accordance with the present invention.

Figure 2 is a top plan view thereof.

Figure 3 is a bottom plan view of the device, and

Figure 4 is an enlarged transverse cross section taken substantially upon the line 4-4 of Figure 2 and disclosing the device being used for the sealing of an envelope.

Now having particular reference to the drawing, my novel sealer consists of a water container 5 of elongated formation and preferably of square shape in cross section which serves also as a handle for the sealer. The outer end of this container is provided with a threaded nipple 6 for receiving a conventional threaded cap, not disclosed, this construction being provided for permitting of the ready filling of said container. As indicated in Figure 1 the opposite end of the container 5 is closed, while leading from the bottom wall thereof is a longitudinal

tongue 7 preferably of the same material from which the container is constructed, said tongue being formed at a slight angle with respect to the container so that when the tongue is arranged beneath the flap *a* of an envelope A in substantially horizontal position, the container 5 will be raised diagonally with respect thereto so that the hand will not encounter the envelope nor the desk upon which the same is disposed.

The closed end of this container 5 is formed at its lower edge with an opening 8 through which is arranged a moistener wick 9, one end thereof being disposed within the container, while the opposite end is extended longitudinally upon the top side of the tongue 7. The longitudinal and end edges of this tongue 7 are bent over upon the end and edges of the wick 9 to provide retaining pins therefor, as indicated by the dotted lines in Figure 2 and the full lines in Figure 4.

As clearly disclosed in the last mentioned figure, the thickness of the wick material upon the tongue 7 is such that the top surface thereof will be partially above the inner edge of the said pins so that the gummed surface of the envelope flap *a* will be encountered.

The end wall of the container 5 is formed in spaced relation above the tongue 7 with a second longitudinal tongue 10 in parallel relation with said first mentioned tongue 7, the second mentioned tongue being of greater length than the first mentioned tongue to extend therebeyond as indicated in Figures 2 and 3. Furthermore, the forward edge of the said tongue 7 is in rearwardly spaced relation with the edge of the tongue 10 so as to enable the flap *a* to be readily engaged therebetween. The rear edge of the tongue 10 is formed with a slightly raised longitudinal extension, 11, the ends of which are formed with depending ears 12-12 within which are mounted the end pintles of a pressure roller 13 of a diameter that the bottom surface thereof will be beneath the wick carrying tongue 7 so that when the flap *a* is arranged beneath the roller 13 and above the tongue 7, a longitudinal movement of the sealer will cause the moistening of the under and gummed surface of the flap and the immediate downward pressure of the flap against the envelope body by the roller 13 to cause the same to tightly adhere to the body.

It will thus be seen that I have provided a

highly novel, simple, and relatively inexpensive envelope sealer that is well adapted for all the purposes heretofore designated and even though I have herein shown and 5 described the invention as consisting of certain detail structural elements it is nevertheless to be understood that some changes may be made therein without affecting the spirit and scope of the appended claim.

10 Having thus described the invention, what I claim is:—

15 In an envelope sealer of the character described, a liquid container of a shape to provide a handle, an extension at one end of the container, the same projecting from the bottom side thereof, and at oblique relation to 20 the said container, the adjacent end of said

25 container being formed with an opening, a wick adapted to rest upon said extension and to project through said opening and within 20 the container, the longitudinal edge of said extension being bent upon the wick to secure the same in position, a tongue projecting outwardly from the end of the container, in spaced parallelism with the extension, one 25 longitudinal edge of said tongue being adapted to project beyond one longitudinal edge of the extension and is provided with a pair of spaced depending ears, and an elongated roller rotatably mounted between said 30 ears so that the same will depend below the plane of the extension.

In testimony whereof I affix my signature.
OLIN M. DANTZLER.
